UNITED STATES PATENT OFFICE.

JAMES E. WRIGHT, OF BAY CITY, MICHIGAN.

HOOP-FORMING MACHINE.

1,426,028.

Specification of Letters Patent. Patented Aug. 15, 1922.

Application filed April 19, 1920. Serial No. 375,016.

To all whom it may concern:

Be it known that I, JAMES E. WRIGHT, a citizen of the United States of America, residing at Bay City, in the county of Bay and 5 State of Michigan, have invented certain new and useful Improvements in Hoop-Forming Machines, of which the following is a specification.

This invention relates to hoop forming 10 machines and the like.

One object of the invention is to design a machine which will bend green or dry stock into hoops at a comparatively high rate of speed and with absolutely no breakage 15 whatsoever.

A further object is to provide a machine which will bend any specie of timber into hoops or strips of wood for various other purposes and which will also bend cross-grained wood with practically no breakage. 20

A further object still is to provide a very simple compact and inexpensive machine which will pucker or crimp the inner surface of the strip and which will also stretch 25 the outer surface so that it may be readily formed as required.

With the above and other objects in view, the present invention consists in the combination and arrangement of different parts, 30 hereinafter more fully described, illustrated in the accompanying drawings, and more particularly pointed out in the appended claims, it being understood that changes may be made in the form, size, proportion and 35 minor details, without departing from the spirit or sacrificing any of the advantages of the invention.

In the drawings:

Fig. 1 is a side view of my improved hoop 40 or strip forming machine.

Fig. 2 is a front view thereof.

Fig. 3 is a top plan view.

Fig. 4 is an enlarged fragmentary sectional view illustrating the crimping roller 45 and the hoop.

Fig. 5 is a side view of a similar machine showing it provided with a flexible endless steel belt or chain, and

Fig. 6 is a side view of the same.

Fig. 7 is a top plan view of the same, and

Fig. 8 is a fragmentary view of a crimping wheel which can be used for forming the corners on strips used for square boxes.

In the hoop industry it has heretofore been 55 impossible to form hoops out of dry material, it being absolutely necessary to use

green timber and then steam or boil the timber in order that the hoops may be readily formed, also, it has been necessary to use a certain kind of timber, exclusively for this 60 purpose, said timber being grained lengthwise, and being peculiarly adapted when steamed, for the making of hoops. With my improved machine any kind of timber can be used regardless of the grain, the 65 hoops being coiled dry and being equal in every way to the elm hoop now in use, driving equally as well on the barrel, requiring less machinery to make, bringing about a great saving in timber, and being easier to 70 handle in every way, this machine can also be used for making strips for various other purposes and I do not wish to be confined merely to the making of hoops.

In the accompanying drawing I have 75 shown two alternate forms of my improved hoop forming machine, the preferred form being shown in Figs. 1, 2 and 3 of the drawings, and the alternate form being shown in Figs. 5, 6 and 7. This machine comprises 80 frame members 10 which are adapted to rest on the floor, being secured together in any approved manner, a crimping wheel 11 formed in the shape of a gear and provided around its outer periphery with a plurality 85 of crimping teeth, being carried on a shaft member 12 set in suitable bearings journaled in the frame of the machine, and has bolted thereto the upstanding flange members 13 which act as guides for the stock as 90 it is being fed through the machine. Located directly above the said crimping wheel is a pressure roller 14 journaled in boxes 15 slidably mounted on the frame, and being provided with a compression spring 16 interposed between the top of the frame and the said pressure roller 15 so that upon manipulation of the adjusting wheel 17, any desired pressure can be exerted on the pressure roller, and it will be understood that 100 said pressure roller is free to move vertically in the machine to accommodate the stock as it is being fed beneath same.

In practise the hoops are formed with a beveled side in order that they will conform to the bilge of the barrel when formed, and it is therefore necessary that the outer edge of the teeth on the said crimping wheel be slightly beveled to conform thereto, and in order that the pressure roller may not 105 continuously ride on the flanges of the crimping wheel when stock is not feeding through

the machine, a set screw 18 is provided being threaded into the frame directly beneath the bearings 15, and acting as a stop to limit the downward movement of the said pressure roller. For guiding the stock around the crimping wheel and preventing the lateral displacement thereof, a flexible belt 19 is secured in a slotted opening 20 in the frame of the machine, this belt comprises a plurality of small roller members 21, which as the stock travels around the crimping wheel, tends to stretch the outer surface thereof, the teeth on the crimping wheel crimping the inner side of the hoop and making it more flexible, that is, puckering the wood which would otherwise have to be compressed, in order to allow the hoop to be formed, this flexible belt extends around in under the machine, the end thereof, being held by spring tension which can be of any convenient form. In the present instance I have shown it as attached to a lever 22 which I have pivoted to a portion 23 of the frame 10, a rod member 24 being pivotally secured to the opposite end of the lever, thence extending through a suitable opening formed in the member 25 secured to the frame, and provided with a threaded end portion on which an adjusting nut 26 is threaded, a compression spring 27 being interposed between the member 25 and the adjusting nut 26, for exerting a continuous tension on the said flexible belt.

One of the frame members 10 is provided with a laterally extending arm 28 in which one end of the shaft member 16 is journaled, a spur gear 29 being mounted on the said shaft and is adapted to mesh with a spur pinion 30 which is in turn driven in any suitable manner from any source of power, this is however immaterial, as the machine can be driven in a number of different ways.

The flanges 17 which act as a guide for the stock also act as a protection for the teeth on the crimping wheel, for instance, when the machine is running and no stock is passing through same, the pressure roller (should the adjustment permit) will ride on the said flanges, as will also the rollers comprising the flexible chain, the stock however being of sufficient thickness to extend slightly above the top of the said flanges as shown in Fig. 4. The stock which is cut to a pre-determined length is fed into the machine by the operator standing directly in front thereof, the pressure roller forcing the stock down until the teeth bite into and crimp the said stock, thence striking the end of the flexible belt or chain, raising same, as shown in dotted lines, to allow the stock to feed therebeneath and around the crimping wheel.

In Fig. 5 an alternate form of belt is shown, this belt comprising an endless chain revolving around the gear members 31 set

in suitable bearings journaled in the frame, one of the bearings being slideable and having a spring tensioned adjustment to compensate for the thickness of stock feeding through the machine, this adjustment being of the usual type as used in different classes of work, or a plain steel band can be used with equally favorable results.

I wish to direct particular attention to the crimping wheel and the flexible belt which are the most essential features of my invention, this wheel does not cut or destroy the fibre or grain of the wood, merely crimping or waving it on the inner surface, making it flexible and easy to bend, therefore the outer surface of the hoop need not be excessively stretched to allow it to be formed to shape, and such stretching as is necessary is performed by this plurality of rollers or chain, which kneads the outer surface while maintaining a continuous pressure thereon.

From the foregoing description it will be obvious that I have perfected a very simple and economical hoop forming machine, capable of forming the uncooked timber of any kind, either cross-grained or straight grained, into satisfactory and saleable hoops.

What I claim is:

1. A hoop forming machine comprising a frame, a crimping wheel mounted in the frame and having crimping teeth to engage the inner face of the stock, a flexible member extending partially around the crimping wheel concentric with the same and provided at intervals with means for engaging, kneading, and stretching the outer face of the stock while the opposite portion of the inner face is being crimped, and means for rotating the crimping wheel.

2. A hoop forming machine comprising a frame, a crimping wheel having crimping teeth to engage the inner face of the stock, a flexible belt extending partially around the crimping wheel concentric with the same and provided at intervals with rollers engaging, kneading, and stretching the outer face of the stock while the opposite portion of the inner face of the same is being crimped, and means for rotating the crimping wheel.

3. A hoop forming machine comprising a frame, a crimping wheel mounted in the frame and provided at opposite sides with circumferential guide flanges and provided between the same with laterally bevelled crimping teeth for engaging the inner face of the stock, a flexible member extending partially around the crimping wheel concentric with the same for pressing the stock against the said teeth of the crimping wheel, and means for rotating the crimping wheel.

4. A hoop forming machine comprising a frame, a crimping wheel mounted in the frame, a flexible member extending partially around the crimping wheel concentric

with the same and secured at one end to the no stock is in the machine, and means for frame, a lever pivoted between its ends and rotating the crimping wheel.

5. A hoop forming machine comprising connected at its inner end with the free end of the flexible member, and a tensioning device connected with the outer end of the lever.

5. A hoop forming machine comprising a frame, a crimping wheel mounted in the frame and provided with crimping teeth to engage the inner face of the stock, said crimping wheel being provided at opposite sides with circumferential flanges, a flexible belt extending partially around the crimping wheel concentric with the same and provided at intervals with rollers arranged to engage and knead the outer face of the stock, said flanges of the crimping wheel being arranged to receive and support the flexible belt to prevent the same from coming in contact with the crimping teeth when

6. A hoop forming machine comprising a frame, a crimping wheel mounted in the frame and provided with crimping teeth 25 arranged to engage the inner face of the stock, said crimping wheel being also provided at opposite sides with projecting circumferential flanges, a flexible member extending partially around the crimping 30 wheel concentric with the same for holding the material against the crimping teeth, a spring tensioned pressure roller mounted above the crimping wheel and adapted to engage the stock and adjustable stops arranged to limit the downward movement of the pressure roller to prevent the same from riding on the said flanges.

In testimony whereof I affix my signature.

JAMES E. WRIGHT.
